Specification for Design.

Patented Sept. 22, 1914.

Application filed October 18, 1913. Serial No. 796,088. Term of patent 7 years.

To all whom it may concern:

Be it known that we, CORNELIUS J. FIELD and RAYMOND CILLEY, citizens of the United States of America, and residents of Brooklyn, Kings county, State of New York, whose post-office addresses are 149 Broadway, New York city, New York, have invented a new, original, and ornamental Design for a Body for Electrical Omnibuses or other Vehicles, of which the following is a specification, reference being had to the accompanying drawings, forming part thereof.

In these drawings, Figure 1 is a side view,

and Fig. 2 an end elevation, of a vehicle body that embodies our new design.

What is claimed is:

The ornamental design for a body for electrical omnibuses or other vehicles, as shown.

In testimony whereof we have signed this specification in the presence of two subscribing witnesses.

CORNELIUS J. FIELD.
RAYMOND CILLEY.
